United States Patent Office

Des. 183,756
Patented Oct. 21, 1958

183,756

BREAD BOX

Michael Lax, New York, N. Y., assignor to Kromex Corporation, Cleveland, Ohio, a corporation of Ohio

Application November 8, 1957, Serial No. 48,402

Term of patent 14 years

(Cl. D44—5)

Fig. 1

Fig. 2

Fig. 3

Fig. 4

Fig. 5

Fig. 1 is a front elevational view of a bread box, embodying my new design;

Fig. 2 is a top plan view of the bread box;

Fig. 3 is a side elevational view of the bread box, as viewed from the right side of Fig. 1;

Fig. 4 is a fragmentary cross-sectional view, on an enlarged scale, taken on the line 4—4 of Fig. 1; and

Fig. 5 is a fragmentary cross-sectional view, on an enlarged scale, taken on the line 5—5 of Fig. 1.

I claim:

The ornamental design for a bread box, substantially as shown.
